SAMPLING DEVICE

Lewis Tucker Baker, Jacksonville, Fla., assignor
to Southern Lock Joint Stave Company, Inc.,
Jacksonville, Fla., a corporation of Florida

Application September 15, 1933, Serial No. 689,665

2 Claims. (Cl. 217—72)

This invention relates to sampling devices and more particularly to devices adapted for sampling barreled substances, such, for example, as rosin, without removing the top of the barrel or 5 container.

Sampling devices in accordance with the present invention are adapted for extracting samples of various different substances, but for the purposes of illustration a sampling device constructed in accordance with my invention will be described as used in connection with the extracting of samples of rosin from barrels. It will be understood, however, that devices in accordance with my invention may be used for extracting 10 samples of other substances from containers in general.

Heretofore the practice generally followed in extracting samples of rosin from barrels has been to remove the top of the barrel and to break out 20 a sample from the top of the rosin contained in the barrel. This practice is objectionable in that after the rosin at the top of the barrel is broken for permitting the removal of a sample and the top boards of the barrel replaced, rain water is 25 apt to find its way into the barrel and to spoil the rosin. Furthermore, breaking of the rosin at the top of the barrel followed by replacing the barrel top more or less loosely results in loss of some of the broken rosin when the barrel is moved around.

30 In accordance with my invention, I extract a clean, true sample from a barrel or other container through a small opening in the container, which opening normally is covered by a closure which is adapted to be removed and replaced 35 easily.

An object of my invention is to provide an improved device for extracting samples from a barrel or the like in the manner generally set forth above, i. e., in such a way as to dispense 40 with the necessity of removing the top of the barrel. Another object is to provide a device of a character referred to by means of which a clean, smooth, truly representative sample may be extracted without its being subject to the marring 45 action of a cutting tool or to unusual conditions, such as local heating which, if present, would change the properties of the sample so as to render the latter different from the contents of the container. Other objects will become apparent from a reading of the following description, the appended claims, and the accompanying drawing, in which:

Figure 1 is a perspective view of a barrel showing the application thereto of a sampling device 55 in accordance with my invention;

Figure 2 is a perspective view drawn on an enlarged scale and showing a portion of a barrel equipped with a sampling device in accordance with my invention;

Figure 3 is a perspective view of my improved sampling device showing two separable parts thereof separated one from the other;

Figure 4 is a perspective view of the sampling device shown in Figure 3, the separable parts being shown in assembled relation;

Figure 5 is a sectional view taken on the line 5—5 of Figure 2;

Figure 6 is a view similar to Figure 5 but drawn on a reduced scale and showing a tool for assisting the removal of the sampling device from the 15 barrel; and

Figure 7 is a sectional view taken on the line 7—7 of Figure 6.

By way of illustration a preferred embodiment of my improved sampling device is illustrated in 20 connection with a barrel A provided with a top filler opening 1, and with an aperture 2 in its side wall. The sampling device generally designated B comprises a hollow sample-receiving part 3 of considerably smaller cross section than the 25 aperture 2 and a pair of supporting parts or arms 4—4 extending laterally from the sample-receiving part 3 and being adapted to be secured to the side wall of the barrel adjacent to the aperture 2 for supporting the sample-receiving 30 part 3 in the barrel in spaced relation to the periphery of the aperture 2 and in substantial axial alignment with the latter. Preferably, the supporting arms 4 include portions 5 adapted to lie against the wall of the aperture 2 and flanges 6 35 adapted to lie against the outside of the container wall immediately adjacent the aperture 2.

The sample-receiving part 3 may comprise two 40 separable sections 3^a and 3^b adapted to be assembled as in the illustrated form by telescoping one within the other. As shown the section 3^b is adapted to be set telescopically within the section 3^a.

It will be understood that it is desirable that 45 the sampling device be so arranged that the sample can be removed easily therefrom after the device itself has been removed from the barrel, and to this end the sections 3^a and 3^b preferably are constructed in such manner that their respective walls may be sprung apart somewhat for releasing the sample. In the illustrated form the section 3^a comprises a back wall 7, two side walls 8—8, and flanges 9—9 extending along the forward edges of the side walls, but terminating in spaced relation one from the other. 50 55

The section 3^b is channel-shaped and comprises a back wall or web 10 and side walls or flanges 11-11. Usually when the sections 3^a and 3^b are separate the sample will remain in the section 3^b. The sides 11-11 of this section may be sprung apart easily in case the sample has any tendency to stick. If, however, the sample should remain lodged in the section 3^a after the sections are separated, the sides 8-8 also may be sprung apart slightly to release the sample without breaking it. Thus, an important feature of the invention resides in the provision of an expandible sample-receiving part whose walls may be sprung apart relatively outwards from the sample to release the latter without breaking it.

In use, the sampling device B is inserted through the aperture 2 and positioned as shown best in Figure 2 with the supporting parts 4 holding the sample-receiving part 3 in the position shown and the wall 7 of the section 3^a closing the space between the free edges of the flanges 11 of the channel-shaped section 3^b. In order to close the aperture 2 a spring metal cap closure 12 is inserted in the aperture and nails or other fastening means are driven through the cap and preferably through the supporting parts 4 and into the barrel wall. The container is then filled through the top opening 1, which then is closed by any suitable means. When the molten rosin is poured into the barrel it, of course, will fill the hollow part 3 of the sampling device which is open at both of its ends, thus permitting it to be filled readily.

In order to obtain a true sample of the hardened rosin the nails 13 are withdrawn and the closure 12 is removed. The supporting arms 4 are then bent outwardly into parallelism with the axis of the sample-receiving part 3 as shown in Figure 6. Thereafter the rosin surrounding the sample-receiving part 3 is loosened by means of a hollow cutting tool 14 which is of greater diameter than the sample-receiving part 3 and which is of slightly smaller diameter than the aperture 2. This will permit the sampling device to be removed bodily from the barrel after which the sections 3^a and 3^b are separated and the clean, smooth, true sample is dislodged from the section 3^b or the section 3^a as the case may be. It is apparent that a sample obtained in this manner will be truly representative of the rosin within the barrel since the sample has not been subjected to any cutting action, heating, or other modifying conditions.

By the use of my device it is unnecessary to remove the top of the barrel and to break the rosin therein in order to secure a sample. I thus eliminate the damage to the rosin caused by rain water seeping through the top head and lying on the broken rosin. Furthermore, by using my device there will be no loss of broken rosin sifting out through cracks in and around the head where barrels are rolled or handled. The time necessary to obtain a sample and hence the expense of sampling is greatly reduced. Since it is unnecessary to remove the barrel top in order to obtain a sample, it is possible to construct the barrel in such a manner that the top fits into a croze in the same manner as the bottom whereby the barrel is greatly strengthened. With this construction, if the barrel is stored for any length of time and if the bottom shows a tendency to rot, the barrel may be up-ended so as to position the top wall underneath and in this way the barrel will remain in good condition for a much longer time than when the barrels rest on their bottom heads only during the entire time they are in storage.

Although a practical and the at present preferred form of my invention has been shown and described for the purposes of illustration, it will be understood that various modifications may be made in the specific construction and arrangement of the parts without departing from the invention as defined in the claims.

I claim:

1. The combination with a container having a wall with an aperture therein; of a sampling device including a hollow part of less cross sectional width than said aperture positioned in said container in axial alignment with said aperture for receiving a sample; a supporting arm extending from said hollow part to said wall and being secured thereto for supporting said hollow sample-receiving part in said container in alignment with said aperture in spaced relation with the periphery thereof, said supporting arm being adapted to be bent outwardly into substantial parallelism with the axis of said aperture to permit use of a hollow cutting tool for removing said device from said container; and a closure for said aperture fitting over said device and being detachably secured to said container.

2. A combination as set forth in claim 1 in which the hollow sample-receiving part comprises two separable sections.

LEWIS TUCKER BAKER.
